UNITED STATES PATENT OFFICE.

JOSEPH ROBERT HAUPENTHAL, OF AUBURN, NEW YORK.

BOOT OR SHOE HEEL.

No. 826,504.

Specification of Letters Patent.

Patented July 17, 1906.

Application filed March 2, 1905. Serial No. 248,164.

To all whom it may concern:

Be it known that I, JOSEPH ROBERT HAUPENTHAL, a citizen of the United States, residing at Auburn, in the county of Cayuga and State of New York, have invented a new and useful Improvement in Boot and Shoe Heels, of which the following is a specification.

My invention relates to articles for footwear, like boots and shoes, in which the heels of the same are provided with rubber to relieve the jar consequent upon walking or otherwise; and the objects of my improvement are to furnish boot and shoe heels with a piece or section of rubber that may be readily and permanently attached thereto, while of less weight and of less expense than the ordinary so-called "rubber heel," and that shall offer no impediment to the wearer from the catching of corners over and above that afforded by the heels of boots or shoes as ordinarily made and without any rubber attachment.

I attain the objects above named by the arrangement of parts shown in the drawings forming a part of this specification, in which—

Figure 1 is a side view of a portion of a boot or shoe with the lifts of the heel thereon shown in section and my improvement attached thereto. Fig. 2 is a view of the bottom part of the heel shown in Fig. 1 and illustrates the form or shape of the rubber section attached thereon. Fig. 3 is a view of my improvement detached from the heel of the boot or shoe and shows the flap or flange forming a part of said rubber section. Fig. 4 is a view similar to Fig. 3, but shows said rubber section provided at its rear end with countersunk screw-holes for additional fastening of the same in place on the said heel of the boot or shoe when deemed expedient. Fig. 5 is a plan view of the flap or flange, the dotted lines therein showing the position of the rubber section with relation to the same.

Similar reference-figures refer to similar parts in the several views.

Referring to Fig. 1, 1 shows the vamp or front of the boot or shoe; 2, the quarter or counter; 3, the shank, and 4 the several lifts comprising the heel of the same, which are attached in the ordinary way and which need no further description.

As usually constructed, the so-called "rubber heel" covers the entire bottom of the last or bottom lift, being secured thereto by screws or nails passing in holes provided for

that purpose in the same. Usually the said rubber heel is of the thickness, more or less, of one of the lifts and when fastened in place frequently requires trimming to make it conform to the shape and size of the heel, which process entails some labor and the expenditure of time as well. After being in use for a period of time the said rubber heel is apt to bulge or swell out at its edge beyond the lifts to which it is fastened, presenting thus an appearance of untidiness unless retrimmed, which would tend to weaken its elasticity. The corners of the rubber heel at the forward end are constantly liable to catch against obstacles and otherwise to annoy the wearer, while the bottom or tread surface of the same, owing to its elasticity, is apt to impede movement, especially in dancing or gliding on the floor.

My improvement tends to mitigate, if not wholly eradicate, the objectionable features mentioned by providing a section of rubber 5, which may have a roughened or corrugated tread, if desired, provided with a flange or flap 6, which holds the former in desired place on the bottom of the heel of the boot or shoe. The said section of rubber 5 is preferably of the form I have shown in the several figures and is placed on the rear end of the heel, the flange or flap 6 being uppermost. The said section of rubber 5 and the flange or flap 6, it will be evident, may be made each separate from the other and suitably cemented together, or the two members may be formed in a single homogeneous piece of rubber. In such case it will be seen a choice of material for the flange or flap may be had, which can be of leather, webbing, or any stock suitable for the purpose, and its thickness regulated to meet the needs of the case. The space left at the forward end of the heel is fitted or filled in by a section of leather 7, (see Figs. 1 and 2,) the rear end of which conforms to and fits the shape or contour of the forward end of said rubber section 5, and being of the same thickness thus presents a smooth and unbroken surface for the bottom of the heel.

The several parts named are preferably adjusted and fastened on the heel of the boot or shoe in the following manner: The flange or flap 6 of the rubber section 5 is properly cemented and nailed in place on the lifts of the heel next above it, the rubber section 5 of course being downward and at the rear of said heel. The piece of leather 7, or more

appropriately the sectional lift, already described, may, if so desired, be cemented in place against the bottom of the said flange or flap 6 and further secured to the whole by a row or rows of nails 8 at either side thereof. The several parts described being thus arranged and secured in desired place, it will be observed that when the flap or flange and the rubber section are formed of a single piece of rubber the former offers a yielding and protected cushion over the entire area of the heel above said rubber section, while the tread of the latter at the rear of the heel provides, primarily, the elasticity and spring at the point most desired—that is, where the outer end of the heel strikes the ground or floor first—and there being no rubber exposed forwardly the usual catchings of the corners, as has been mentioned, are avoided.

In Fig. 4 I have shown the rubber section 5 provided rearwardly with three countersunk holes 9, which, if deemed desirable, may be utilized for the further security of the same on the heel, although in practice it has been found that the cementing and pegging of the flange or flap of the same is amply sufficient. It will also be seen that should the said rubber section bulge or swell beyond the edge of the lift above less trimming of the same will be required than where the rubber covers the entire surface of the heel.

It will be evident from my description of the several parts and their arrangement and relation to each other that a saving of rubber is had, as well as less time and trouble in placing the same on the heel. Where my improvement is placed on the heels of footwear in large quantities, it will be found the

nails fastening the leather piece 7 may be driven in a pegging-machine after the usual 40 method.

Having thus described my improvement and the several parts comprising the same, what I claim as new, and desire to secure by Letters Patent of the United States, is— 45

A heel for boots and shoes comprised in its entirety of a section or rubber and a flap secured thereto and projecting therefrom, the former having its rear end rounded and having two side portions which extend inwardly 50 from points substantially midway the combined lengths of the rubber section and flap, to a common point located adjacent the termination of said flap, and a section of leather shaped to correspond to the side portions of 55 said rubber section and in intimate contact therewith, whereby the joint between said leather and rubber is formed at points substantially central of the length of the heel, and wherein the rubber gradually decreases 60 to a single central point as the front of the heel is approached, the outer faces of said leather and rubber being flush with one another whereby a walking tread is formed of substantially half leather and half rubber, 65 the rubber being nailed to the lift of the boot or shoe heel, and the leather being nailed to the rubber and said lift.

In testimony whereof I have signed my name to this specification in the presence of 70 two subscribing witnesses.

JOSEPH ROBERT HAUPENTHAL.
